UNITED STATES PATENT OFFICE.

WILLIAM H. WORKMAN, OF BEVERLY, MASSACHUSETTS.

GAME APPARATUS.

1,371,831.

Specification of Letters Patent. Patented Mar. 15, 1921.

Application filed August 19, 1918. Serial No. 818,442.

To all whom it may concern:

Be it known that I, WILLIAM H. WORKMAN, a citizen of the United States of America, residing at Beverly, in the county of 5 Essex and State of Massachusetts, have invented new and useful Improvements in Game Apparatus, of which the following is a specification.

The object of the invention is to provide 10 a relatively simple and at the same time compactly foldable game apparatus adapted for use in playing games involving the exercise of a certain degree of skill involving the principle of the operation of a universally mounted pendulum and to this end 15 the same consists in a construction and combination of parts hereinafter described, it being understood that changes in form and proportion may be resorted to within the 20 scope of the claims without departing from the principles involved.

In the drawing:

Figure 1 is a perspective view of the apparatus with the displaceable pieces set up 25 in position for playing one of the games for which the apparatus is adapted.

Fig. 2 is a sectional view of the same.

Fig. 3 is a detail view showing the connection between the walls constituting the 30 guard around the playing field.

The apparatus consists essentially of a table 10 upon which are mounted displaceable pieces or pins 11 disposed on end, and a pendulum 12 consisting of a flexible stem 35 universally supported as at 13 and having a weighted ball or bob 14, said pendulum being adapted to be swung under the directive control of the operator to bring the ball or bob into contact with the pins under such 40 conditions as to displace one or more of the latter at each play, and it being understood that the seats or stations of the pins or the pins themselves may be lettered, numbered, or otherwise designated to indicate value as 45 a means of counting or making scores when two or more players engage in the game. The table is preferably provided with sockets 15 forming seats for the reception of the extremities of the pins or playing 50 pieces 11 and is supported by legs 16 upon a floor or bottom 17 constituting the playing board. The field represented by the surface of this board is preferably surrounded 55 by a guard consisting of the side walls 18 and end wall 19 which may be hinged to

gether at 20 to permit of folding, the inner surfaces of said walls being grooved as at 21 to receive the edges of the floor or bottom 17, and the side walls being held in engaging relation with said floor or bottom 60 by means of thumb nuts 22 engaged in terminal threaded stems 23 on the boards or elements forming the floor or bottom. By this construction the apparatus can be knocked down to permit of folding and 65 packing in compact shape for storage or transportation. A sectional standard 24 is secured by a thumb bolt 25 or its equivalent at one corner of the inclosure, preferably at a short distance from the table and is 70 provided with a horizontally extending arm 26 which terminally supports the pendulum. The supporting point of the pendulum is preferably to one side of the table or the pin-supporting area, and when idle or 75 hanging vertically and at rest the pendulum is preferably located opposite the forward portion of the pin-supporting arm.

The game is played by grasping the ball or bob and drawing it back to or beyond the 80 rear wall 19 and then releasing it with a swinging or directing movement which will cause it to describe an arc passing to the front of the playing area so that upon the return swing it will come in contact with the 85 pin or pins to cause their displacement or removal from the stations in which they are placed upon the supporting area.

Obviously any suitable rules may be adopted for the playing of the game, and the number of different games involving different degrees of skill may be devised to increase the interest or difficulty of operation, the general principle, however, being that the universally supported swinging ball or bob 90 is to be so directed or delivered by the operator as to cause it to describe a forward path without contact with the playing pieces or pins and to contact with said pins 95 in order to make a point or points upon the return swinging movement. Obviously where the players are less skilful it is possible to provide for the playing of games in which the ball or bob might be delivered from the opposite direction so as to contact 100 with the pins on the forward swinging movement.

What is claimed is:

1. A game apparatus having a playing field consisting of a floor or bottom, side 110

and end walls hingedly connected and provided in their inner surfaces with grooves for the reception of said floor or bottom, means for securing said walls in operative relation with the floor or bottom, a table detachably mounted upon the floor or bottom within the space inclosed by said walls and forming a support for movable playing pieces or pins, a standard detachably supported by said walls and having an arm extending over the playing field, and a universally supported pendulum suspended from said arm and having a terminal ball or bob for traversing the surface of said table.

2. A game apparatus having a playing

field consisting of a floor or bottom, side and end walls hingedly connected and provided in their inner surfaces with grooves for the reception of said floor or bottom, means for securing said walls in operative relation with the floor or bottom, a table detachably mounted on the floor or bottom within the space inclosed by said walls, the said table forming a support for movable playing pieces or pins, and an impact element mounted to traverse the surface of said table for impact with the playing pieces thereon.

In testimony whereof I affix my signature. 30

WILLIAM H. WORKMAN.
